Patented Dec. 16, 1975

238,061

TIRE

Andre E. J. Baus, Welsdorf, Luxembourg, assignor to
The Goodyear Tire & Rubber Company

Filed Feb. 28, 1974, Ser. No. 446,995

Claims priority, application Great Britain Nov. 9, 1973

Term of patent 14 years

Int. Cl. D12—15

U.S. Cl. D12—148

The figure is a perspective view of a tire showing my new design, it being understood that the design is repeated throughout the circumference of the tire as shown schematically by solid lines, the opposite side being substantially the same as that shown.

I claim:

The ornamental design for a tire, substantially as shown and described.
